SPHERICAL ASHTRAY

Walter I. Bieger, Minneapolis, Minn., assignor to Arthur Salm Inc., Chicago, Ill., a corporation of Illinois

Filed Dec. 23, 1968, Ser. No. 15,092

Term of patent 14 years

Int. Cl. D27—03

U.S. Cl. D85—2

FIG. 1.

FIG. 2.

FIG. 3.

FIG. 4.

FIG. 5.

FIG. 1 is a perspective view of a spherical ashtray incorporating my new design, the top portion thereof being rotated to the opening position;

FIG. 2 is a side elevation view of the spherical ashtray of FIG. 1, the opposite side being a mirror image thereof;

FIG. 3 is a front elevation view of a spherical ashtray incorporating my new design, the top portion being rotated to the closed position;

FIG. 4 is a rear elevation view of the spherical ashtray of FIG. 3; and

FIG. 5 is a plan view of the spherical ashtray of FIG. 3.

I claim:

The ornamental design for a spherical ashtray, substantially as shown and described.
